[57] CLAIM

The ornamental design for a storage trunk for a pickup truck, as shown and described.

DESCRIPTION

FIG. 1 is a rear perspective view of a storage trunk for a pickup truck embodying my new design;

FIG. 2 is a perspective view thereof with the lid in open condition;

FIG. 3 is a side elevation view thereof;

FIG. 4 is a front elevation view thereof;

FIG. 5 is a rear elevation view thereof; and

FIG. 6 is a fragmentary bottom plan view thereof.

Fig. 1.Fig. 2.Fig. 3.Fig. 4.Fig. 5.Fig. 6.
